UNITED STATES PATENT OFFICE.

JOSEPH H. PICKARECK, OF DETROIT, MICHIGAN, ASSIGNOR TO SQUARE D COMPANY, OF DETROIT, MICHIGAN, A CORPORATION OF MICHIGAN.

ELECTRICAL SWITCH AND INTERLOCKING CASING.

1,412,488.

Specification of Letters Patent. Patented Apr. 11, 1922.

Application filed May 9, 1918. Serial No. 233,429.

To all whom it may concern:

Be it known that I, JOSEPH H. PICKARECK, a citizen of the United States, residing at Detroit, in the county of Wayne and State of Michigan, have invented new and useful Improvements in Electrical Switches and Interlocking Casings, of which the following is a full, clear, and exact specification.

My invention relates to electrical switch of the general type having an enclosing casing, of metal, or other suitable material, insulated from the electrical contacts of such switch, of the general type known as armorclad switches.

One of the objects of my invention is, to equip a switch of this general type with an interlocking cover and switch mechanism whereby it is impossible to open the cover of such casing without first opening the switch, or, in other words, throwing it to an "off" position. These switches perform a very desirable function in that they prevent workmen or others from coming into contact with the live parts of the switch, under normal conditions, for, when the cover is open, the switch is always in an "off" position. However, these switches equipped solely as above stated, have the serious defect of rendering it impossible for an inspector to examine the switch mechanism or to run a test while the switch is in "on" position. Therefore, when an inspector or test man inspects such switch, it is always necessary to shut off the consumers' power before such inspection can be made.

It is, therefore, a further object of my invention to so design the interlocking mechanism that such mechanism may be temporarily rendered ineffective by an authorized person suitably equipped with a key or similar means whereby access may be had to the interior of the casing while the switch is closed and also whereby the switch may be closed while the cover is open. It will, therefore, be seen that a suitably equipped authorized person may inspect the switch mechanism without interfering with the customer's power, as he may then open the box or casing without first opening the switch.

It is a further object of this invention to so design the interlocking mechanism that at the completion of the test or inspection

such interlocking mechanism may be again rendered operative or effective.

It is a further object of this invention to 55 so design the armorclad switch that it may, under normal conditions, be operated from the outside while the cover is in closed position.

It is a further object of this invention to 60 simplify the construction of armorclad switches and to design a very rugged and practically foolproof structure.

It is a further object of the invention to 65 so design the armorclad switch that it is impossible to close such switch while the cover is open.

One of the embodiments of the present invention is shown in the accompanying drawings forming a part of this specification 70 wherein similar parts are designated by similar reference characters.

Fig. 1 is a perspective view of the armorclad switch with the cover closed and the switch thrown in "on" position and with interlocking mechanism in effective or operative position.

Fig. 2 is a perspective view of the armorclad switch with the switch mechanism in "on" position and the interlocking mechanism in inoperative or ineffective position with the cover partly open; and

Fig. 3 is a perspective view of the armorclad switch with the cover open showing the interior of such mechanism with the switch 85 in "off" position.

Referring now to the drawing in detail, 1 represents the bottom portion of the armorclad switch casing and 2 the upper or cover portion. Such portions are hingedly connected at 3 and may be locked in closed position through the medium of the opening 4 in the cover and the apertured projection 5 passing therethrough, whereby a padlock may be used to securely lock said cover in 90 closed position. The details of the electrical portion of the switch mechanism is not shown in this case but may be of any suitable type. Only so much of the switch is shown as cooperates with the interlocking mechanism. 100 Said electrical switch is operated by a U-shaped member 6 pivotally related to the base of the box at each side thereof and provided with an external handle 7, whereby

such switch mechanism may be operated even when the box is closed and locked. This U-shaped member 6 carries a lug 8 with a projecting finger 9, which projecting finger, 5 therefore, describes an arc of a circle whose center is on a line joining the two points at which said U-shaped member is pivoted. A laterally movable strap member or bar 10, which is also formed on the arc of a circle 10 concentric with that described by the finger 9, is provided in a curved recessed portion of the box top and is guided in its lateral motion by suitable slots 11 cooperating with pins 12. The guiding pins 12 are rigidly 15 fastened in the cover 2 and the arcuate member 10 slides in the recessed portion 13 of such cover. Such arcuate member 10 is designed to engage under the finger 9 throughout the major portion of the stroke or travel 20 of such finger 9, that is to say, from the "on" position almost to the completion of its stroke to the "off" position. It will thus be seen that while such switch is in closed or "on" position, such cover is prevented from 25 being opened by the engagement of such arcuate member with the finger 9. However, when the switch is in "off" position, the finger 9 passes clear of the extreme rear end of such arcuate member and the cover 30 may then be opened.

To secure one of the objects of the invention, namely, freedom or flexibility of operation desired by the test man or inspector, whereby he may open the cover while the 35 switch is in "on" position, the arcuate member 10 is provided with an outwardly or laterally-extending controlling arm or bar 14 which extends through an aperture 15 in the wall of the top of the box and may be 40 operated through the medium of the handle 16, whereby the member 10 may be caused to engage or disengage the finger 9. Alining openings 17 are provided in a lug 18 rigidly fastened to the top of the box and in 45 the lateral arm 14, whereby such arcuate member 10 may be locked in engagement with the finger 9 throughout the major portion of the stroke of such finger by a padlock 19 having its hook or bail-shaped portion 20 passing through the alining openings 17. The test man or meter man is provided with a key fitting such lock 19 whereby he may render the interlocking mechanism temporarily ineffective.

55 Referring now to Fig. 3, it will be seen that such figure shows the interior of the box omitting the enclosed switch mechanism. The electrical portions of such switch, that is to say, knife blades and cooperating 60 contacts and fuses are not shown but may be similar to those shown in the application of B. D. Horton No. 228,636, filed April 15, 1918. In this figure the switch is shown in "off" position temporarily locked in such 65 position. This locking mechanism, whereby

it is impossible to close the switch without first closing the box, comprises a projecting member 21 bolted or fastened upon one of the arms of the U-shaped operating member and lying directly in the path of a small 70 arcuate member 22. Such member 22 is rigidly fastened to the cover 2 and the center of curvature of both its interior and exterior edges is approximately on the axis of the hinges of said cover 2 whereby, when 75 the cover is opened, said member 22 projects through an opening 23 in the lower portion 1 of the box. It will thus be seen that, upon attempting to close the switch, the member 21 contacts with the member 22 80 and thereby renders such closing of the switch impossible. When the box cover 2 is closed, such member 22 is withdrawn from the path of motion of the member 21 and the switch may then be closed. Projecting from the top of the box interiorly and downwardly is an arm 24 which, when the cover is closed, lies in the path of movement of one of the arms of the U-shaped 85 operating member 6. This arm 24 does not normally engage the U-shaped member 6 but only engages such member when the U-shaped member is thrown to the extreme 90 limit of motion in its "off" direction, that is to say, when one of the arms of such U-shaped member contacts with the stop 25. The operation of this "lock off" mechanism takes place when the following cycle of operations is performed, namely, when the switch is thrown to its extreme "off" position, while the box top is open and the box top 100 thereafter closed. It will thus be seen that the member 24 then lies above one of the arms of the U-shaped member 6 and prevents such member from moving over so as 105 to throw the switch in the "on" position. The cover may then be locked in closed position by means of a suitable padlock passing through the apertured member 5, whereby the switch is permanently locked in "off" 110 position.

The box is provided with suitable knock-outs 26 to accomodate a particular type of wiring. The box is further provided with angle irons 27 riveted adjacent its corners 115 and also with an opening at each end 28, whereby any desired type of end plate may be removably held in position, either by the medium of bolts or screws passing through openings 29 or simply by the top 120 of the box which securely locks such end plates in position when said top is closed.

It will thus be seen that a very simple and effective mechanism has been designed 125 which has a great number of interrelated functions, for example, cooperating, interlocking, cover and switch mechanism, means whereby such interlocking may be rendered ineffective by a suitably equipped authorized person and cooperating elements 130

whereby it is impossible to close such switch without first closing the box and, further, with means whereby said switch may be permanently locked in "off" position.

It is to be understood that the above specifically described form is only one of many possible forms of devices for securing these desired results and such specific description and drawings, must, therefore, be considered as illustrative and not limiting the invention to the specific form shown, except as hereinafter defined by the following claims.

Having thus described my invention what I claim as new and desire to secure by Letters Patent of the United States, is:—

1. In an enclosed switch, in combination, a casing provided with a cover removable to afford access to the switch, an arcuate member non-rotatively mounted on the inside of the cover, and switch operating means co-operating with the arcuate member to normally lock the cover when the switch is closed, the switch operating means being adapted to engage with said member during a substantial portion of its movement from one position to the other by reason of the arcuate formation of the member.

2. In an enclosed switch, in combination, a casing provided with a cover removable to afford access to the switch, an arcuate member non-rotatively mounted on the inside of the cover, and switch operating means carrying a finger engaging with the arcuate member to normally lock the cover when the switch is closed, said finger engaging said arcuate member during a substantial portion of the movement of said switch operating means from one position to the other.

3. In an enclosed switch, in combination, a casing provided with a cover removable to afford access to the switch, an arcuate member non-rotatively mounted on the inside of the cover, and switch operating means carrying a finger normally engaging the arcuate member when the switch is closed and disengaged from the arcuate member when the switch is open, whereby the cover is normally locked only when the switch is closed, said finger engaging said arcuate member during a substantial portion of the movement of said switch operating means from one position to the other.

4. In an enclosed switch having a casing provided with a recessed cover, the combination of an arcuate member slidably mounted in said recess and movable with the cover, and switch operating means co-operating with the arcuate member to normally lock the cover when the switch is closed.

5. In an enclosed switch, in combination, a casing provided with a recessed cover, an arcuate member slidably mounted in the re-

cess and movable with the cover, and switch operating means carrying a finger normally engaging the arcuate member when the switch is in closed position, and disengaged from the arcuate member when the switch is opened, whereby the cover is normally locked when the switch is closed.

6. In an enclosed switch, in combination, a casing provided with a recessed cover, carrying guide pins, an arcuate member slidably mounted in such recess and provided with guiding slots co-operating with said guiding pins, said member being movable with the cover, and switch operating means co-operating with the arcuate member to normally lock the cover when the switch is closed.

7. In an enclosed switch, in combination, a casing provided with a cover, an arcuate member carried by the cover and movable therewith, switch operating means cooperating with the arcuate member and in substantial engagement with said member during a substantial portion of the movement of said switch operating means from one position to another, an interlocking controlling means for moving said arcuate member into and out of cooperative relation with said switch operating means whereby normally the switch operating means and cover are interlocking, and a removable lock cooperating with said interlocking controlling means for normally insuring said interlocking, the interlock being rendered ineffective by removal of the lock and subsequent manipulation of said interlocking controlling means.

8. In an enclosed switch, in combination, a casing provided with a cover, an arcuate member carried by the cover and movable therewith, switch operating means carrying a finger engaging with the arcuate member during a substantial portion of the movement of said switch operating means from one position to another, an interlocking controlling means for moving said arcuate member into and out of cooperative relation with said switch operating means whereby normally the switch operating means and cover are interlocking, and a removable lock cooperating with said interlocking controlling means for normally insuring said interlocking, the interlock being rendered ineffective by removal of the lock and subsequent manipulation of said interlocking controlling means.

9. In an enclosed switch, in combination, a casing provided with a cover, an arcuate member carried by the cover and movable therewith, switch operating means carrying a finger normally engaging the arcuate member during a substantial portion of the movement of said means from one position to another and when the switch is closed, and disengaged from the arcuate member

- when the switch is open whereby the cover and switch are normally interlocking, an interlocking controlling means, and a removable lock cooperating with said interlocking controlling means normally insuring such interlocking, the interlocking being temporarily rendered ineffective by removal of the lock and subsequent manipulation of said interlocking controlling means.
10. In an enclosed switch, in combination, a casing provided with a cover, an arcuate member carried by the cover and movable therewith, switch operating means cooperating with the arcuate member during a substantial portion of the movement of said means from one position to another, whereby normally the switch operating means and cover are interlocking, and means comprising a laterally extending controlling arm fastened to said arcuate member and a removable lock whereby the interlocking may be rendered temporarily ineffective by the removal of the lock and subsequent manipulation of the interlocking controlling means.
15. An enclosed switch, in combination, a casing provided with a cover having guiding pins, an arcuate member having guiding slots co-operating with said guiding pins and movable with the cover, switch operating means co-operating with said arcuate member whereby normally the switch operating means and cover are interlocking, and means whereby the interlocking may be rendered temporarily ineffective.
20. 11. An enclosed switch, in combination, a casing provided with a cover having guiding pins, an arcuate member having guiding slots co-operating with said guiding pins and movable with the cover, switch operating means co-operating with said arcuate member whereby normally the switch operating means and cover are interlocking, and means whereby the interlocking may be rendered temporarily ineffective.
25. 12. In an enclosed switch, in combination, a casing provided with a cover, an arcuate member carried by the cover and movable therewith, switch operating means cooperating with said arcuate member whereby normally the switch operating means and arcuate member are interlocking, a laterally extending movable controlling arm fastened to said arcuate member, said controlling arm having means whereby it may be temporarily locked in position relative to the cover to render the switch and cover interlocking.
30. 13. In an enclosed switch, in combination, a casing provided with a cover, a laterally slidible bar carried internally by the cover, and switch operating means co-operating with said bar and normally rendering said switch and cover interlocking, of means whereby the interlocking may be rendered temporarily ineffective.
35. 14. In an enclosed switch, in combination, a casing provided with a cover having guiding pins, a laterally slidible bar provided with guiding slots co-operating with the guiding pins carried by the cover, switch operating means co-operating with said bar and normally rendering said switch and cover interlocking, and means whereby the interlocking may be rendered temporarily ineffective.
40. 15. In an enclosed switch, in combination, a casing provided with a cover, a laterally slidible bar carried by the cover, switch operating means co-operating with said laterally slidible bar and normally rendering said switch and cover interlocking, and means whereby said interlocking may be temporarily rendered ineffective, comprising a laterally extending controlling arm secured to said slidible bar.
45. 16. In an enclosed switch, in combination, a casing provided with a cover, a laterally slidible bar carried by the cover, switch operating means co-operating with said laterally slidible bar and normally rendering said switch and cover interlocking, and means whereby said interlocking may be temporarily rendered ineffective, comprising a laterally extending controlling arm secured to said slidible bar, said controlling bar having means whereby it may be temporarily locked in position to render said switch and cover interlocking.
50. 17. In an enclosed switch, in combination, a casing provided with a cover having guiding pins, a laterally slidible bar having guiding slots co-operating with said guiding pins, movable with said cover, and switch operating means co-operating with said laterally slidible bar whereby the cover and switch are normally interlocking, and means whereby the interlocking may be rendered temporarily ineffective, comprising a laterally extending controlling arm secured to said laterally slidible bar and provided with means, whereby it may be temporarily locked in position to render said switch and cover interlocking.
55. 18. In an enclosed switch casing provided with a cover, interlocking members carried by said cover, one of said members comprising an arcuate bar with which said switch operating means cooperates to lock the cover closed when the switch is closed, and the other of said members comprising a member adapted to be projected through and into the casing when the cover is open to interlock the switch operating means open when the cover is open, and interlocking disabling means comprising an exteriorly accessible interlocking controlling member for moving said bar whereby the cover may be opened while the switch remains closed.

JOSEPH H. PICKARECK.
